FLUID-DISCHARGE DEVICE

Leon Kardorff, Jamaica, and Charles M. Gold, Franklin Square, N.Y., assignors to Yardney International Corp., New York, N.Y., a corporation of New York
Filed Jan. 26, 1960, Ser. No. 4,639
6 Claims. (Cl. 136—90)

The present invention relates to a fluid-discharge device as used, for example, for activating electrochemical batteries of the deferred-action or reserve type wherein one or more dry-charged cells are supplied with electrolyte liquor in response to a predetermined signal.

Various systems have been proposed heretofore wherein in a frangible diaphragm, originally blocking the passage of electrolyte from its storage container to the battery, is pierced or shattered in response to the activating signal so that the liquor can flow through the breach. In order to reduce the activation delay to a minimum, it is desirable to place the liquor under sufficient pressure to make its 15 irruption into the battery substantially instantaneous. Such pressure, however, should come into existence only at or immediately prior to the time of intended activation so as not to cause premature rupture of the diaphragm.

In one prior system, disclosed in pending application Ser. No. 416,468 filed March 16, 1954, now Patent No. 3,018,314, by Emanuel Cooper and Charles M. Gold, the activating signal releases a charge of compressed gas which then acts upon the electrolyte and through it upon the diaphragm, urging the latter into contact with a stationary puncturing device. This system performs satisfactorily with certain types of flexible diaphragms, especially plastic membranes having an inwardly facing bulge which reverses its curvature in response to pressure from the electrolyte, but is not readily adaptable for use with, for example, a metallic diaphragm designed to be ruptured by a pivoting cutter as disclosed in co-pending application Ser. No. 4,806, filed on even date herewith by Charles M. Gold, one of the present joint inventors.

It is, therefore, an object of the present invention to provide an improved activator for the purpose described, having means for positively synchronizing the application of pressure to a fluid (e.g. an electrolyte liquor) with the operation of a movable cutter for rupturing a diaphragm in the path of such fluid.

It has, furthermore, been found desirable, particularly in conjunction with relatively rigid diaphragms such as steel disks, to delay the application of pressure to the fluid until the cutter has begun to puncture the diaphragm, thereby avoiding the risk of creating leakages elsewhere in the system. It is, accordingly, another object of the invention to provide means for so timing the two operations as to insure the desired delay.

In accordance with this invention there is provided, in a fluid-discharge device such as a battery activator, a cutter movably positioned adjacent a diaphragm blocking the outflow of a fluid from a reservoir, a source of compressed gas adapted, when released, to exert pressure upon the fluid, and a preferable electrically actuatable operating member poised to displace the cutter in a diaphragm-rupturing sense, this member being linked via a delay device (e.g. a lost-motion connection) with a gas-releasing element associated with the aforementioned source whereby the gas is liberated to exert pressure upon the fluid after a predetermined interval following the beginning of the diaphragm-cutting operation.

The operating member may be actuated in a variety of ways, advantageously by the impact resulting from the release of a stored force such as, for example, the detonation pressure of an explosive charge which is set off in response to an external signal effecting the closure of

2

an electrical circuit. This member may then be in the form of a plunger adapted to be propelled by the release of the stored force, the plunger in a preferred embodiment having an abutment (e.g. an edge of a slot) which, after a travel of the plunger over a certain distance, engages a break-off point on a nozzle of a cartridge in which the compressed gas is stored whereby this gas is released into a duct leading to a piston (e.g. an inflatable bladder) adapted to exert pressure upon the electrolytic liquor to be discharged.

The invention will be described in greater detail with reference to the accompanying drawing in which:

FIG. 1 is a side-elevational view, partly in section, of an activating device embodying the invention;

FIG. 2 is a cross-sectional view taken on the line II—II of FIG. 1; and

FIG. 3 is a top plan view, taken on the line III—III of FIG. 1, of a distributor for an electrolytic liquor to be discharged from a reservoir by the activator.

The drawing shows a system for the instantaneous activation of a dry-charged battery 10 whose several cells 11 are adapted to be supplied, via a U-shaped manifold 12, with electrolyte entering the manifold through a conduit 13. Each cell 11 contains a conventional electrode assembly, e.g. of silver-oxide positive plates and zinc negative plates separated by layers of paper or other highly permeable sheet material, which can be irrigated from the manifold 12 through a respective filling tube 14 whose open lower end terminates directly above the cell bottom so as to cause filling from below. The tubes 14 advantageously extend in opposite directions from the branches of the manifold 12 at an acute angle, alternately forwardly and rearwardly as best seen in FIG. 3, whereby a simultaneous draining of all the cells upon a tilting of the assembly in any direction will be avoided.

The electrolyte, e.g. a concentrated solution of potassium hydroxide, is initially stored in a reservoir 15 provided at opposite ends with an inlet 16 and an outlet 17. Inlet 16 represents the termination of a gas duct 18 which at that point communicates with the interior of an inflatable bladder 19 extending within the reservoir toward outlet 17. This outlet is originally blocked by a preferably metallic diaphragm 20, e.g. a disk of stainless steel a fraction of a millimeter in thickness, and is covered inside the reservoir by a shield 21 in the form of a perforated cap curved toward the bladder 19. Diaphragm 20 is adapted to be ruptured by a cutter 22 having the shape of a bell-crank lever pivotable about a pin 23 within a chamber 24, the depending arm 22a of this lever being generally triangular and terminating in a knife point which penetrates the diaphragm and slits it open in an upward direction upon a counter-clockwise swinging of the cutter (as viewed in FIG. 1) about its pivot 23. Such swinging is normally prevented by a safety stud 25, of a relatively soft metal such as copper, serving to hold the cutter 22 against chattering and striking against the diaphragm.

The horizontal arm 22b of lever 22 is in contact with a plunger 26 entering the chamber 24 at a location approximately opposite that at which the chamber communicates with the conduit 13 leading to the cells 11 of battery 10. Plunger 26 is slideable within a cylinder 27 whose extremity remote from chamber 24 is closed by a plug 28 supporting a squib 29. The charge of the squib can be detonated by the closure of a switch (not shown) connecting it, via wires 30, to a suitable source of electric current. Cylinder 27 has two lateral bosses 31, 32, boss 31 receiving the inlet end of gas duct 18 whereas boss 32 is traversed by a discharge nozzle 33 of a cartridge 34 containing a charge of compressed gas. Nozzle 33 terminates in a closed nipple 33a from which it is separated by a constriction 33b. Nipple 33a is re-

ceived with clearance in a slot 35 of plunger 26 in such manner that the upper edge of the slot strikes the nipple after the plunger has been forced downwardly, by an explosion of squib 29, for a sufficient distance to cause an initial rupture of diaphragm 20 by cutter 22; stud 25 yields under the pressure of the explosion as indicated in dot-dash lines in FIGURE 1. The coupling of nipple 33a with plunger 26 via slot 35 represents a lost-motion connection which delays the exertion of pressure upon the liquid in reservoir 15, through the break-off of the nipple to release gas from cartridge 34 via duct 18 into bladder 19, until after the diaphragm 20 has been at least sufficiently weakened to be quickly ruptured by the pressure of the liquid and the continuing action of cutter 22 whereby damage to the reservoir 15 or other parts of the apparatus is effectively prevented.

It will be apparent that lost-motion connections other than the one specifically described and illustrated may be used in an apparatus embodying the invention.

What is claimed is:

1. In a deferred-action battery in combination, a reservoir containing fluid electrolyte and having an electrolyte outlet end; a diaphragm normally blocking said outlet end; gas pressure operated means adapted to propel said electrolyte from said reservoir into the battery; a source of compressed gas provided with a normally blocked gas-release means; means connecting said compressed gas source with said pressure-operated means when said gas-release means is open; cutter means operatively mounted for cutting said diaphragm; and consecutively operating means adapted to operate said cutter

means and to unblock said gas-release means whereby said cutter is caused to cut said diaphragm and said gas is conveyed to said pressure-operated means.

5 2. A deferred-action battery according to claim 1 wherein said consecutively operating means in a piston adapted to engage said cutter means and then said normally blocked gas release means.

10 3. A deferred-action battery according to claim 2 wherein said normally blocked gas release means is a nipple closing off said compressed gas source.

15 4. A deferred-action battery according to claim 2 wherein said pressure operated means is an inflatable bag disposed inside said reservoir.

5 5. A deferred-action battery according to claim 2 including a squib positioned to move said piston on detonation.

10 6. A deferred-action battery according to claim 2 wherein said diaphragm is a cuttable metal diaphragm.
